UNITED STATES PATENT OFFICE.

RALPH J. PATTERSON, OF BERLIN, NEW HAMPSHIRE.

ELECTRICAL WATER-HEATER.

1,329,204.

Specification of Letters Patent. Patented Jan. 27, 1920.

Application filed August 20, 1919. Serial No. 318,793.

To all whom it may concern:

Be it known that I, RALPH J. PATTERSON, a citizen of the United States, residing at Berlin, in the county of Coos and State of New Hampshire, have invented certain new and useful Improvements in Electrical Water-Heaters, of which the following is a specification.

This invention relates to new and useful improvements in water heaters and more particularly to that type of heater in which the heating medium consists of a resistance or heating coil.

An important object of the invention is to provide means whereby the heating coils of the heater may be made readily accessible and removable.

A further object of the invention is to provide a heating unit which may be used either within the boiler or merely placed in the pipe line adjacent thereto.

A further object of the invention is to provide such a heater, which is cheap to manufacture, and the parts of which are readily accessible for changes in event of their being destroyed through long usage.

Other objects and advantages of the invention will be apparent during the course of the following description.

In the accompanying drawings forming a part of this specification and in which like numerals are employed to designate like parts throughout the same,

Figure 1 is a side elevation of a boiler illustrating one use of my heater,

Fig. 2 is a sectional view taken through the boiler, showing a slightly modified form of heater adapted for use within the boiler.

Fig. 3 is a vertical section taken through the heater, the coils being shown in elevation,

Fig. 4 is a section on line 4—4 of Fig. 3, and,

Fig. 5 is a section on line 5—5 of Fig. 3.

Referring now more particularly to the drawings, the numeral 10 designates a boiler of a construction usually applied to hot water systems of the general or household type. The numeral 11 designates the cold water inlet pipe and the numeral 12, the hot water outlet pipe.

In the form shown in Fig. 1, my heater is shown as being connected between the drain pipe 13 of the boiler and a branch pipe 15, connected with the hot water outlet pipe 12,

the heater being designated as a whole by the numeral 14.

The heater comprises the tubular casting 16, having a central opening 16' provided at its lower end with screw-threads adapted to receive the cold water inlet pipe 11 or a branch pipe from the boiler drain pipe 13. At its upper end, the tubular casting is provided with a horizontal flange 17, having an upstanding rim 18. The rim 18 is provided with interior screw-threads 19 for a purpose hereinafter to appear. Formed in the horizontal flange 17 are openings 20, adapted to receive casings 21, the casings 21 being rolled or beaded into a groove 22, formed in the sides of the openings 20 of the flange 17 to form a securing means to obtain a watertight joint. These casings are closed at their upper ends and are joined together by a baffle plate 23, secured to these ends. 70 Mounted within the tubular casings 21 are coils 24, each coil comprising an outer insulation covering 25, within which is arranged a resistance 26 wound about a core 27. The coils are connected at their lower ends by 80 means of connectors 28, mounted upon the binding posts 29 of the coils.

Mounted about the tubular casting 16 is a washer 30, having a cut-out portion 31, this washer being held in position against 85 the under side of the horizontal flange 17 by a retaining ring or clip 32, which may be formed of spring metal or the like. This ring is seated in a suitable groove formed in the outer face of the tubular casting 16. 90 By referring to Fig. 5, it will be clearly seen that by shifting this washer, the various coils may be inserted in the casings 21 and when the coils are all in place, by placing the washer in the position shown in the 95 above mentioned figure, they are securely held in position.

A bottom cover plate 33 is provided, having a central opening 34, adapted to receive the tubular casting 16. The cover plate 33 is provided with an opening 35, through which the lead-in wire may be inserted for attachment to the coils 24. The cover plate is held in position by means of spring clips 36, bearing on their free ends, pins 27, which extend through suitable openings formed in the plate and engaged in openings 38, formed in the outer side of the horizontal flange 17. It will readily be seen that the cover plate 33 is readily removable to allow 110

access to the coils 24, and that these coils may be readily removed by simply shifting the washer 30.

A hood 39 is provided to cover the coil casings 21, and baffle plate 23, this hood being provided adjacent its lower end with external screw-threads adapted to engage the external screw-threads of the upstanding rim 18. To form a water-tight joint, a 10 gasket 40 may be placed intermediate the lower end of the hood and the horizontal flange 17 and the hood screwed down upon the gasket.

At its upper end, the hood is provided 15 with a flanged outlet fitting 42, riveted or otherwise secured thereto, as at 41, this outlet fitting being provided with screw-threads to receive the hot water outlet pipe 15.

In the form shown in Fig. 2, it becomes 20 necessary to provide the upstanding flange 18 with screw-threads 43 upon its outer surface. The bottom of the boiler 44 is provided with corresponding threads to receive the threads 43 and the heater is screwed 25 tight into position in the bottom of the boiler or may be gasketed or a tight joint formed in any desired manner. In this construction, the cold water admitted to the boiler passes through the heater. As water 30 is only admitted to the heater when a faucet is opened or water is being drawn in any manner from the hot water outlet pipe 12, in order to insure perfect circulation, the hood 39 is provided adjacent its lower edge 35 with openings 45, through which the cold water may enter the heater, establishing a circulation through the pipe 15, as is well known.

It is to be understood that the forms of 40 my invention herewith shown and described are to be taken as preferred examples of the same, and that various changes in the shape, size, and arrangement of parts may be resorted to without departing from the 45 spirit of my invention, or the scope of the subjoined claims.

Having thus described my invention, I claim:

1. In a water heater, a tubular casting 50 provided with a flange, an opening formed in said flange, a heating coil extending into said opening, and means surrounding said tubular casting allowing insertion of said coil in said opening when in one position and preventing removal of the coil when shifted.

2. In a water heater, a tubular casting provided with a flange, an opening formed in said flange, a casing secured within said 60 opening, a heating coil adapted for insertion in said casing, and means surrounding said tubular casting and rotatable thereon allowing insertion of said coil in said casing when in one position and preventing re- 65 moval of the coil when shifted.

3. In a water heater, a tubular casting provided with a flange, an opening formed in said flange, a tubular casing secured within said opening, a heating unit adapted for insertion in said casing, a washer provided 70 with a cut-out portion surrounding said tubular casting, and means for retaining said washer in position against the under side of said flange.

4. In a water heater, a tubular casting 75 provided with a flange, a plurality of openings formed in said flange, tubular casings secured in said openings, heating units adapted for insertion in said casings, a washer mounted about said tubular casting and rotatable thereon, and means for retaining 80 said washer in position against the under surface of said flange, said washer being provided with a cut-out portion, adapted to co-act with the openings formed in said 85 flange to allow of insertion or removal of said heating units.

5. In a water heater, a tubular casting provided with a flange, an opening formed 90 in said flange, a tubular casing secured within said opening, a heating unit adapted for insertion in said casing, a washer provided with a cut-out portion surrounding said tubular casting, means for retaining said washer in position against the under side of 95 said flange, and a removable cover surrounding said tubular casting and provided with means for releasably securing the same to said flange.

6. In a water heater, a tubular casting 100 provided with a flange, having an upstanding rim provided with internal screw-threads, a plurality of openings formed in said flange, tubular casings secured in said 105 openings, heating units adapted for insertion in said casings, means for removably securing said heating units within said casings, and a hood provided with an outlet opening, said hood being provided upon its outer face with screw-threads adapted to 110 engage the screw-threads formed in said rim.

7. In a water heater, a tubular casting provided with a flange having an upstanding rim provided with internal and external 115 screw-threads, a plurality of openings formed in said flange, tubular casings secured in said openings, heating units adapted for insertion in said casings, means for removably securing said heating units within 120 said casings, and a hood provided with an outlet opening adapted to cover said casings and said flange, said hood being provided upon its outer face with screw-threads adapted to engage the internal screw-threads 125 formed upon said rim.

8. In a water heater, a tubular casting provided with a flange, having an upstanding rim provided with internal screw-threads, a plurality of openings formed in 130

said flange, tubular casings secured in said openings, heating units adapted for insertion in said casings, means for removably securing said heating units within said casings, a baffle plate secured to the upper end of said casings, a baffle plate secured to the upper end of said casings, and a hood provided with an outlet opening, said hood being provided upon its outer face with screw-threads adapted to engage the screw-threads formed in 10 said rim.

9. In a water heater, a tubular casting provided with a flange having an upstanding rim, having internal and external screw-threads, a plurality of openings formed in 15 said flange, tubular casings having their upper ends closed secured in said openings,

heating units adapted for insertion in said casings, means for removably securing said heating units within said casings, a baffle plate secured to the upper ends of said casings, a hood provided with external screw-threads adapted to engage the screw-threads of said rim, an outlet opening for said hood, and a plurality of openings formed in said hood adjacent the lower end thereof. 20 25

In testimony whereof I affix my signature in presence of two witnesses.

RALPH J. PATTERSON.
